UNITED STATES PATENT OFFICE

118,806

DESIGN FOR A BLOUSE OR SIMILAR ARTICLE

Louis Kliban, South Norwalk, Conn.

Application November 22, 1938, Serial No. 81,285

Term of patent 7 years

To all whom it may concern:

Be it known that I, Louis Kliban, a citizen of the United States, residing in South Norwalk, county of Fairfield, State of Connecticut, have invented a new, original, and ornamental Design for a Blouse or Similar Article, of which the following is a specification, reference being had to the accompanying drawing, forming part thereof.

The characteristic feature of my design resides in the combination on the blouse disclosed of the specific yoke and stitching arrangement on the front, as shown.

The back of the blouse is conventionally plain.

I claim:

The ornamental design for a blouse or similar article, as shown and described.

LOUIS KLIBAN.
